UNITED STATES PATENT OFFICE.

LOUIS WEGLEIN, JR., OF PHILADELPHIA, PENNSYLVANIA.

COMBINATION REFLECTING DEVICE AND SOUND-CONVEYER.

No. 927,910.

Specification of Letters Patent.

Patented July 13, 1909.

Application filed February 6, 1909. Serial No. 476,396.

To all whom it may concern:

Be it known that I, LOUIS WEGLEIN, Jr., a citizen of the United States, residing in the city and county of Philadelphia, State of Pennsylvania, have invented a new and useful Combination Reflecting Device and Sound-Conveyer, of which the following is a specification.

This invention relates to window mirrors and more especially to the combination of a sound conveyer and mirror adapted to be positioned outside of a window.

In window mirrors as heretofore constructed it has been impossible, where a roof or an extension of roof has been built over the doorway of a house, to see the reflection of a person standing at the door and therefore a very important feature of such devices is rendered useless.

By my present invention, I am enabled to see everything that takes place adjacent the doorway and recognize persons who have rung the bell and if it is inconvenient to go down to the door, I can by simple adjustment of the device provide a means for holding conversation with them from the window above.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a section of a portion of a house and porch roof showing my device in operative position. Fig. 2 represents a vertical section on an enlarged scale of the device with the parts in a different position from that shown in Fig. 1. Fig. 3 represents a detail of the locking clip.

Similar numerals of reference indicate corresponding parts in the figures.

Referring to the drawings, 1 designates a tube formed of suitable material and preferably having the shape of a frustum of a cone, the end having the largest diameter being provided with means for engagement with a

suitable support and in the present instance with an outwardly projecting flange 2 having openings 3 therein, serving to permit suitable fastening means to engage the flange 2 and hold the tube 1 in proper position. It will be apparent that this shape tube will readily serve efficiently as a sound conveying device, the diverging sides transmitting the sound and increasing the volume thereof.

Mounted adjacent the top end or opening of the tube 1 is a mirror or other suitable reflecting device which is so positioned with respect to the tube that a person looking into the mirror from the front of the same will see reflected thereon the objects or persons beneath the tube.

4 designates a collar adapted to fit around the tube 1 and in the present instance, to be held thereon by means of bolts 5 or equivalent means, the position of the collar being adjacent the smaller opening of the tube.

6 designates ears here shown as formed integral with the collar 4 and spaced apart a sufficient distance to receive and permit movement of an arm 7 which is preferably mounted for pivotal movement on the ears 6 by means of a bolt 8 or the like. This arm 7 extends downwardly for a portion of its length and is then curved upwardly so that its end is adjacent the top of the tube 1 and in such a position as to permit a cap 9 pivotally mounted thereon to completely close the opening of the tube when desired and to be positioned properly with respect to the top opening of the tube. As here shown, the cap 9 is suitably recessed to permit the receiving of a mirror 10 therein for a purpose to be presently described.

11 designates suitable lugs secured to the disk 9 and forming with the bolt 12 a pivotal connection between the arm 7 and cap 9.

In order to see the objects or persons below the tube it is desirable to lock or hold the mirror in its proper position therefor so that it will always remain in this position until changed by the user and in the present instance, I employ a spring clip 13 suitably secured to the collar 4, the forks of the spring clip having divergent ends adapted to receive the arm 7 and hold the same firmly in position until released by a pull to overcome the spring of the clip. When the arm 7 is so held, the cap 9 and mirror 10 will be at the proper position with respect to the opening of the tube, as seen in Fig. 1, and it will be noticed that the lower portion of the cap

abuts the arm 7 so that the mirror will be held properly to reflect objects beneath the tube 1.

This device in operation is adapted to be mounted on the roof 14, as shown in Fig. 1, which forms the covering for the door 15 of the house, said tube 4 being positioned on the roof adjacent a window 16, above the door. Of course it will be understood that for correct working of the device an opening should be cut in the roof 14 of a size corresponding to the largest diameter of the tube by which it will be seen that anyone looking out of the window 16 will be able to observe in the mirror 10 anyone standing adjacent the door 15 below. The mirror 10 by means of the pivotal connection to the arm 7 is capable of several different positions and the necessary angle to reflect the image from normal position thereof is shown in Fig. 1 with the arm 7 locked by the clips 13, this being the position to observe who or what is at the door. Should, however, it be desired to talk to anyone at the door below, the cap 9 may be swung back completely out of the way, as seen in dotted line, Fig. 2, so that no obstruction to the tube 1 is presented and the user can speak from the window through the tube to the person at the door.

In bad weather or for other reasons it may

be desired to close the tube 1 and this can readily be done by releasing the arm 7 from the clips 13, overcoming the spring action thereof and the arm 7 can be turned on its pivotal connection with the tube 1, causing the cap 9 to completely cover the top, as seen in full lines, Fig. 2, and at the same time protecting the mirror.

Having thus described my invention, what I claim as new and desire to secure by Letters Patent, is:

1. In a device of the character described, the combination of a sound conveying device, a collar detachably secured at one end, an arm pivoted to said collar, a cap for said device mounted on said arm and a reflecting mirror carried by said cap, and means to lock said arm to maintain said cap in open position.

2. In a device of the character described, a sound conveying device adapted to fit over an opening in a roof, said device having a mouth piece and sides diverging therefrom, a cap for said mouth piece pivoted to said device and a mirror mounted in said cap.

LOUIS WEGLEIN, JR.
